UNITED STATES PATENT OFFICE.

WILLIAM T. BARRATT, OF BENNINGTON, VERMONT, ASSIGNOR, BY DIRECT AND MESNE ASSIGNMENTS, OF ONE-THIRD TO ALEXANDER J. COOPER, AND TWO-THIRDS TO ELIZABETH COOPER STODDARD, BOTH OF BENNINGTON, VERMONT

FEED MECHANISM FOR CIRCULAR-KNITTING MACHINES.

1,191,648.

Specification of Letters Patent.

Patented July 18, 1916.

Application filed October 19, 1912. Serial No. 726,668.

To all whom it may concern:

Be it known that I, WILLIAM T. BARRATT, a citizen of the United States, residing at Bennington, in the county of Bennington 5 and State of Vermont, have invented new and useful Improvements in Feed Mechanism for Circular-Knitting Machines, of which the following is a specification.

This invention relates to improvements in feed mechanism for circular knitting machines, the object of the invention being to provide a feed mechanism whereby one or more courses of a different colored or kind of yarn may be introduced into the main 10 body of the fabric being knit on a circular machine. For example, the machine of this invention may introduce into the body portion of a plain fabric or into the body portion of one kind or color of yarn, first, a circumferential stripe which may be made of several courses of a different color or character of yarn; second, a circumferential stripe which may be made of a single course of a different color or character of yarn; third, 15 the fabric may be knit with a portion of each course containing two yarns and the rest of the course containing a single yarn; fourth, each course may be alternately knit of a plurality of yarns and of a single 20 yarn, thus forming longitudinal stripes in the fabric; fifth, these stripes can be discontinued at intervals longitudinally of the fabric so as to produce a body fabric of one color and at intervals sections of another 25 color forming rectangular portions.

The invention is particularly adapted to be used in connection with spring needle circular knitting machines employing two conical needle cylinders, but the same invention 30 may be used in a machine for doing plain work, or it may be used in a dial and cylinder machine. So long as one cylinder is employed, together with the other essential elements combined and operating therewith 35 substantially as set forth in the following specification and particularly as pointed out in the claims, the invention may be operated without material change and without departing from the spirit of my invention. 40 I have illustrated and described my invention, however, as embodied in a circular rib knitting machine of that type in which two

conical needle cylinders, spring needles and a sinker wheel are employed and of the general type illustrated and described in Letters Patent of the United States issued to me September 12, 1911, No. 1,003,085.

The invention consists in the improved mechanism and devices for automatically controlling the feeding of yarn to the needles 45 of a knitting machine for producing in a tubular knitted fabric a variety of stripes extending partly or wholly around or lengthwise of said fabric, said mechanism and devices being such as to adapt said machine to knit stripes of courses containing a single yarn or a plurality of yarns and furthermore in mechanism for severing the 50 yarn or yarns which at certain times are not being knitted into the fabric, said mechanism and devices comprising particularly 55 1st, the mechanisms for actuating the yarn guides; 2d, a device or devices movable with the needle cylinder for actuating said yarn guide mechanisms; 3rd, the mechanism including a pattern chain for changing the position of said device movable with the needle cylinder so as to operate said yarn guide actuating mechanisms at certain predetermined times; 4th, in the improved sinker 60 wheel and sinkers which coöperate with the yarn guides to take loose ends of yarns leading from said yarn guides and feed them with accuracy and precision to the needles; and 5th, the yarn severing mechanism actuated by the same means which actuates the 65 yarn guide mechanisms, all as set forth in the following specification and particularly 70 75 as pointed out in the claims.

Referring to the drawings: Figure 1 is a front elevation of a portion of a circular knitting machine of the type having two conical needle cylinders and embodying therein my improved striping mechanism. Fig. 2 is a plan view of a portion of the lower cylinder and the instrumentalities 80 constituting one complete feed in connection therewith, with cutters in section. Fig. 3 is a sectional elevation taken on the irregular line 3—3 of Fig. 2 looking in the direction of the arrows on said line. Fig. 4 is a plan view, partly in section, on line 4—4 of Fig. 1, the gear ring of the lower cylinder being indicated in dotted lines. Fig. 5 is a sec-

tional elevation taken on line 5—5 of Fig. 4. Fig. 6 is a development of a section, partly in elevation, taken on line 6—6 of Fig. 2 as viewed in the direction of the arrows on said line, illustrating particularly the needles and their cylinders, a single pair of yarn guides, the pressers for the two sets of needles and the yarn cutting mechanism. Fig. 7 is a plan view of a pair of yarn guides and a portion of the mechanism which operates them. Fig. 8 is a detail sectional elevation taken on line 8—8 of Fig. 2 viewed in the direction of the arrows on said line and illustrating the mechanism for severing the 15 yarn in its relative location to the needle cylinders. Fig. 9 is a detail elevation of a portion of the mechanism for operating the yarn guides and a portion of the mechanism for operating the yarn cutter, the same being viewed in the direction of the arrow α (Fig. 4). Fig. 10 is a side elevation as viewed from the right of Fig. 1, illustrating the pattern chain and a portion of the pattern chain mechanism actuated thereby. Fig. 11 is a detail sectional elevation of a 20 tension device taken on line 11—11 of Fig. 3 as viewed in the direction of the arrows thereon. Fig. 12 is a front elevation of one form of sinker. Fig. 13 is a front elevation of another form of sinker employed in my improved striping machine. Fig. 14 is a detail view of a collar adapted to be used in place of one of the yarn guide actuating cams. Fig. 15 is a plan view illustrating the 25 relative positions of the yarn guides, sinker wheel and sinkers and the cutters. Fig. 16 is a diagram view in elevation of the parts illustrated in Fig. 15 and the position of the yarn leading from both of the yarn guides 30 relatively to the cutters and to the sinkers. Fig. 17 is a view similar to Fig. 16 illustrating the yarn guides in different positions. Fig. 18 is a sectional elevation taken on line 18—18 of Fig. 3. Figs. 19 to 23 are 35 diagrammatic views illustrating different styles of fabric that can be knitted on the machine of this invention.

Like numerals refer to like parts throughout the several views of the drawings.

50 In the drawings, 15 is the frame consisting of side standards 16 and 17 suitably connected together by a cross-head 18. The main driving shaft 19 is journaled to rotate in bearings formed in brackets fast to the 55 frame of the machine and to the cross-head 18. Said driving shaft is rotated by means of a pulley 20 fast thereto, a loose pulley 21 also being provided and adapted to rotate upon the main driving shaft 19.

60 The lower needle cylinder 22 is fast to a running ring 23 rotatably supported upon the bed-plate 24 which, in turn, is supported upon brackets 25 on the side standards 16 and 17. A gear ring 26 is fastened to the 65 running ring 23 and is driven by a pinion 27 fast to a vertical shaft 28 journaled to rotate in suitable bearings 29 and 30 and rotated by means of a bevel gear 31 fast to the lower end of the shaft 28 and meshing into a bevel gear 32 fast to the main driving shaft 19. 78

The upper cylinder 33 is fastened to a gear 34 which, in turn, is fastened to a running ring 35, said running ring being constructed to rotate in the upper bed-plate 36. Said upper bed-plate is adjustably fastened 75 to brackets 37 which, in turn, are adjustably supported upon and fastened to the side standards 16 and 17. The upper cylinder is rotated by means of the gear 34 which meshes into a pinion 38 fast to the vertical 80 shaft 28.

The lower cylinder 22 is provided with a set of spring needles 39 and these are the primary needles. Said needles are adapted to slide in grooves 40 formed in the periphery of the primary cylinder 22. Each of said needles has attached thereto a jack 41 and said needles and their jacks have a reciprocatory motion imparted thereto, in a manner well known to those skilled in the 85 art, by the primary cams 42 fast to brackets 43 which, in turn, are fastened to the bed-plate 24.

The upper or secondary set of needles 44 are mounted to slide in grooves 45 in the 90 periphery of the secondary cylinder 33. These upper needles are provided with jacks 46 which engage cams 47 fast to brackets 48, 49, and thus a reciprocatory motion is imparted to the upper needles in a manner well 95 known to those skilled in this art. The primary needles are pressed to cast off their old loops by a stationary presser 58 and the secondary needles are pressed to cast off their loops by a rotary presser 59, all in a 100 manner well known to those skilled in this art.

The sinkers 50 and 51 are illustrated in detail in Figs. 12 and 13, respectively. These sinkers are mounted upon a sinker carrier 110 or wheel 52 which is fastened to and is rotatable with a gear 53, said gear being rotatably mounted upon a stud 54 fast to a bracket 55 which, in turn, is adjustably fastened to a bracket 56 by means of a set screw 115 57, the bracket 56 being fastened to the bed-plate 24. The gear 53 has a rotary motion imparted thereto by the needles 39 into which the teeth of said gear mesh. The detailed construction of this sinker wheel 120 and the general manner of its operation is fully illustrated in U. S. patent issued to me August 27, 1907, No. 864,354. When the sinker wheel is rotated by the gear 53 a reciprocatory motion is imparted to the sinkers 50 and 51 by the non-rotary cam 52 fast to the stud 54, whereby the same are moved in and out between the primary needles 39 125 in a manner well known to those skilled in the art, and the yarn is thus fed to the primary needles 130

many needles which take said yarn and feed it to the secondary needles in the usual manner. The particular construction, however, and arrangement of the sinkers 50 and 51, whereby the loose end of a yarn is carried by the sinkers 51 into the path of the other sinkers and in between the needles constitutes one of the novel features of my invention in combination with the yarn guides 10 and the particular manner in which these sinkers coöperate with the yarn guides to feed a loose end of the yarn to the primary needles will be more fully described hereinafter. In this embodiment of my invention 15 there are two yarn guides 60 and 61 (see Figs. 3, 6 and 7). The yarn guide 60 consists of a thin strip of metal fastened by a screw 62 to a hub 63. Said yarn guide is fastened as a whole to a rock-shaft 64 adapted 20 to rock in suitable bearings in a bracket 65 which is, in turn, fastened to the bed-plate 24. To the opposite end of the rock-shaft 64 is fastened a rocker-arm 66 and this rocker arm is connected by a link 67 to an arm 68 fast to a rock-shaft 69 journaled 25 in the bracket 65 and having fastened at its opposite end another arm 70 which bears against a cam 71.

The cam 71 is formed of a collar 72 having 30 two cam plates 73 and 74 fastened thereto. Said collar 72 is fastened by a screw 75 to another cam 76 which consists of a hub 77 provided with a flange 78 to which are attached two cam plates 79 and 80. The cams 35 76 and 71 are thus fastened together and rotatable as one piece upon a stud 81 which is fastened to the bracket 65. Said cams are prevented from rotating too freely upon the stud 81 by means of a friction washer 82 and a screw 83 projecting through said washer and having screw-threaded engagement with one end of the stud 81. The yarn guide 61 also consists of a flat piece 40 of metal fastened to a hub 84 by a screw 85 (Fig. 7) and said yarn guide is fastened to a rock-shaft 86 journaled in suitable bearings in the bracket 65, said rock-shaft having fastened to its opposite end a rocker-arm 87 to which is attached a link 88, the lower end 45 of said link (Fig. 9) being fastened to an arm 89 which, in turn, is fastened to a rock-shaft 90 journaled to rock in bearings provided in the bracket 65, and to the other end of the shaft 90, adjacent to the primary cylinder 22, is fastened an arm 91, the free end of which is adapted to bear against the cam 76 (Figs. 3 and 9).

It will be seen that if a rotary motion is 50 imparted to the yarn guide cams 71 and 76, a rocking motion will be imparted to the arms 70 and 91, to the rock-shafts 69 and 90 and to the arms 68 and 89 respectively. Thus, through the links 67 and 88 a rocking motion will be imparted to the arms 55 66 and 87, respectively, and to their rock-

shafts 64 and 84 and thus to the respective yarn guides 60 and 61. A rotary member 92 (Figs. 3, 4 and 5) is fastened to the hub of the cam 76 and this rotary member has a plurality of arms 93 extending radially therefrom and hence said arms are fast to said cam 76. An intermittent rotary motion is imparted to the member 92 and hence to the cams 76 and 71 by means movable with the primary cylinder 22. Said means consists, preferably, of a slide 94 (see Figs. 3 and 4). The slide 94 slides in ways formed in a bracket 95 which is fastened by a clamp 96 and screw 97 to the gear 26, it being understood that the gear 26, running ring 25 and the primary cylinder 22 are fastened rigidly together and constitute, in effect, one piece. The slide 94 is provided with a plurality of notches 98, 99 and 100, and on the side of the bracket 95 is fastened a flat 25 spring 101 bent to form a V-shaped tooth 102 at the free end thereof, and this tooth is adapted to engage in one of the notches 98, 99, 100 and lock the slide 94 in different positions, so that the outer end of the slide which engages the arm 93 of the rotary member 92, in order to impart an intermittent rotary movement to said member may assume positions at varying distances from the center of the needle cylinder 22 as indicated in dotted lines (Fig. 4). The slide is set in different positions as may be desired through instrumentalities operated by a pattern chain which I will now proceed to describe.

The pattern chain 103 is operated by a sprocket 104 rotatably mounted upon a stud 105, an intermittent rotary motion being imparted to said sprocket, and the chain 103 by a ratchet 106 which is fast to the sprocket 104 and to which an intermittently rotary motion is imparted by a pawl 107 which is pivoted at 108 to a rocker-arm 109 fast to a rock-shaft 110 journaled in a bracket 111, which bracket is fastened to the side frame 17, (see Figs. 1, 4 and 10). To the opposite end of the rock-shaft 110 is fastened a cam lever 112 having a roll 113 journaled theron. This roll is adapted to be engaged by a cam plate 114 fast to the running ring 35 of the upper cylinder 33. The running ring 35, gear 34 and upper cylinder 33 are rigidly fastened together and form, in effect, a single piece. The rock-shaft 110 has fastened thereto a rocker-arm 115 which is provided with a stop-screw 116 adapted to abut against the bracket 111 and normally held in contact with said bracket by a spring 117.

It will be seen that as the needle cylinders rotate, the cam plate 114 will engage the roll 113 and rock the cam lever 112, rock-shaft 110 and rocker-arm 109 and actuate the pawl 107 to impart an intermittent rotary movement to the ratchet 106 and sprocket wheel 104, thus moving the pattern chain 125 130 135 140 145 150 155 160 165 170 175 180 185 190 195 198 200 205 210 215 220 225 230 235 103 step by step past and beneath the free end of a rocker arm 118 which is fastened to a rocker-shaft 119 journaled to rock in a bracket 120 fast to the side frame 17 (Figs. 4 and 10). The rock-shaft 119 has fastened thereto another rocker arm 121 (Figs. 1, 4 and 10) which is connected by a link 122 to a rocker arm 123 pivoted at 124 to the side frame of the machine, said rocker-arm being connected by a link 125 to a slide 126. The slide 126 is guided in ways 127 on top of a bracket 128 which is fastened to the cross-head 18. A spring 129 holds the slide 126 normally in engagement with a stop 130 fast to the bracket 128. To the top of the slide 126 are fastened two cam plates 131 and 132, said cam plates forming together a complete cam which is adapted to be engaged by a pin 133 (Figs. 3 and 4), said pin 133 being fastened to the slide 94 and projecting downwardly therefrom, so that as the lower cylinder rotates said pin will pass between the cam plates 131 and 132 and be moved by said cam plates according to the position in which the cam plates are located relatively to said pin, and this location of the cam plates is determined by the pattern chain mechanism hereinbefore described said pattern chain having fastened thereto a plurality of cam blocks 134 and 135. These cam blocks are adapted to engage the free end of the rocker arm 118 as the pattern chain is moved along beneath the same and thus a rocking motion will be imparted to said rocker arm 118 and by it to the rocker-shaft 119, rocker arm 121 and through the link 122 a rocking motion will be imparted to the rocker arm 123 and a reciprocating motion imparted to the slide 126 by said rocker arm through the link 125, so that the cam slide 126, with the cam plates 131 and 132 thereon and constituting a closed cam will be moved to different positions at different distances from the center of the needle cylinders, and as the needle cylinders are rotated by the mechanism hereinbefore described, the pin 133 will be positioned by the cam plates 131 and 132, so that the slide 94 may be positioned with the tooth 102 of the spring 101 in the notch 98 or in the notch 99 or in the notch 100 and when the rocker arm 118 is in the position illustrated in Fig. 10, the slide 94 will be in the position illustrated in Fig. 4. When, however, the cam block 135 is brought beneath the free end of the arm 118, then the cam plates 131 and 132 will be moved out radially slightly and to sufficient extent so that the pin 133, engaging the cam face of the plate 131, will move the slide 94 until the tooth 102 of the spring 101 enters the notch 99. It will be noted that the block 135 is higher than the cam block 134, so that when the block 135 comes beneath the rocker arm 118 said rocker arm 65 will be tipped to a still greater extent than when the cam block 134 was in contact with the free end thereof and for that reason the cam plates 131 and 132 will be moved still farther from the center of the needle cylinder and the pin 133 again engaging the face of the cam plate 131 will move the slide 94 outward radially until the stop tooth 102 enters the notch 100.

The object of setting the slide 94 at different distances from the center of the needle cylinder is to enable the instrumentalities for actuating the yarn guides of different feeds to be actuated, so that if desired the yarn guides for one, two, three or more feeds may be actuated to change the yarn which is being fed to the needles for said feeds. As the needle cylinders rotate, when the slide 94 is in the position illustrated in Fig. 4, then none of the yarn guide actuating instrumentalities will be affected thereby, but if said slide 94 is moved outwardly, as hereinbefore described, until the notch 99 is engaged by the tooth 102, then the outer end of said slide will be in the position indicated in dashed lines (Fig. 4) and marked "a" and when in said position will engage one of the arms 93 on the rotary member 92 of the first feed A, Fig. 4. If the slide 94 is moved to the position in which the tooth 102 engages the notch 98, then the outer end of said slide will be in the position marked "b" (Fig. 4) and as the cylinders rotate will engage one of the arms 93 of the rotary feed member 92 of the feed B (Fig. 4) and also one of the arms 93 of the rotary feed member 92 of the feed A.

It is evident that the number of yarn guide actuating instrumentalities that may be affected by the slide 94 may be multiplied by increasing the distance to which the slide 94 may be moved outwardly from the center of the needle cylinders, this being done by supplying blocks of different heights on the pattern chain 103, and by placing the rotary members 92 of each feed at different distances from the center to correspond with the different distances to which the slide 94 may be projected from said center. The yarn 138 runs from a bobbin 139 (Fig. 3) through a guide tube 140 and through eyes 111 on the yarn guide 60 to the needles. The yarn 142 leads from the bobbin 143 through the yarn guide tube 144 and through eyes 145 on the yarn guide 61 to the needles. A tension device 146 is fastened to the bracket 65 (Figs. 3, 7 and 11), being located intermediate the yarn guides and the bobbins. This tension device consists of a flat piece of spring metal, with the opposite ends bent toward each other to form V-shaped guide arms 147 and 148, the inner face of said device being lined with felt 149 and the device being fastened to the bracket 65 by a screw 150. The yarn 138 contacts with the arm 147 and the yarn 142 contacts 130

with the arm 148. This tension device serves the purpose of preventing the yarn from feeding too freely to the yarn guides and also, after the yarn has been cut by the severing device hereinafter described, said tension device prevents the weight of the yarn from the bobbin pulling said yarn out of position to be operated upon when it is desired to again feed the same to the 10 needles.

It will be understood that when one of the yarn guides carries its respective yarn out of operative position relatively to the needles, said yarn is cut off and this cutting 15 operation is performed by a cutting mechanism consisting of a stationary blade 151 and a pivoted blade 152. The stationary blade 151 is fastened to a bracket 153 which, in turn, is fastened to the upper bed plate 36. 20 The movable cutter 152 is pivoted upon a horizontal pivot 154 which is fastened to a bracket 155 which is also fastened to the bracket 153.

A rocking motion is imparted to the movable cutter blade 152 by a link 156 (Figs. 4, 8 and 9) which is pivotally connected at its upper end to an arm 157 rigidly fastened to the movable cutter blade 152. The lower end of said link 156 is pivotally connected at 30 158 to an arm 159 which is fastened to a rock-shaft 160 journaled to rock in bearings in the bracket 65 and has fastened thereto another arm 161 which terminates at its free end in a cam-shaped plate 162. The cam-shaped plate 162 is adapted to be engaged by the slide 94 when the same is advanced to a sufficient distance from the center of the needle cylinders, as hereinbefore described.

Each of the mechanisms actuating the 40 yarn guides is provided also with a yarn severing mechanism such as hereinbefore described. It is evident that when the slide 94 engages the cam plate 162 on the end of the rocker arm 161, it will depress the 45 rocker arm and thus impart a rocking movement to the rock-shaft 160 and to the rocker-arm 159, and, pulling the link 156 downwardly, will rock the movable cutter blade 152 toward the stationary cutter blade 151 and thus cut the 50 yarn which may be interposed between said blades. The movable cutter blade 152 is held against the stationary cutter blade 151 by a spring 163 which bears thereagainst 55 and encircles the pivotal stud 154 of said cutter blade. The cutters are held open, as shown in Fig. 9, by a spring 164 fast to the lever 127.

The arm 118 may be positioned so as to be 60 engaged by the cam blocks 134, 135 and 136 on the pattern chain 103 or it may be positioned so as to be cleared by said cams, the purpose of this construction being to enable the pattern chain to continue in its 65 movement without producing any effect upon the

instrumentalities whereby the case which operates the slide 94 is moved to different positions relatively to the center of the needle cylinders. The arm 118 (Figs. 4 and 10) has a hub 165 thereon which is provided 70 with a pin 166 fast thereto and adapted to project into either of the slots 167 or 168 formed in a collar 169 fast to the rock-shaft 119.

A spring 170 encircles the rock-shaft 119 between the arm 118 and the arm 121, so that the pin 166 will be kept in one of the slots 167 or 168. When it is in the slot 167 the arm 118 is in the position illustrated in Fig. 10 and in position to be engaged by the 80 cam blocks on the pattern chain. When the pin is in the slot 168, then the arm 118 is in the position illustrated in broken and dotted lines (Fig. 10) and is out of engagement with the pattern chain and its cam blocks. 85 Thus the pattern chain can be immediately thrown out of operation without interfering with the rest of the machine and the mechanisms for actuating the yarn guides can thus be thrown out of operation whenever desired by simply lifting the arm 118 out of engagement with the pattern chain and leaving it out of position.

In order to prevent the free end of the 90 yarn after it has been severed by the cutting mechanism hereinbefore described from springing upwardly and being thrown over one of the yarn guides 60 or 61, a yarn guard 171 is provided which is fastened to a needle support 172 fast to the bracket 48 (Figs. 3 and 6). Said needle support extends downwardly and back of the primary needles adjacent to the sinkers and the guard 171 extends from said support transversely of and above the needles. 100

When the yarn is cut by the mechanism hereinbefore described, the free end of said yarn will drop downwardly to substantially the position illustrated in Figs. 15 and 17 and the yarn thus cut off is held 110 out of the path of the sinkers by the raised position of its respective yarn guide. In order to insure the yarn being fed to the needles when the yarn guide is lowered and in proper position therefor, a certain number, viz., the sinkers 51, are constructed with a projection 173 thereon. This projection 173 is provided on each of the sinkers 51 and extends beyond the outer ends of the sinkers adjacent thereto. Preferably every fourth沉器 in the machine of this invention is made with the projection 173 in accordance with the construction illustrated in Fig. 13, while the other sinkers are made in the usual manner and 120 as illustrated in Fig. 12.

If, instead of feeding a single yarn to form the body portion of the fabric and then throwing off this yarn and throwing in another yarn of a different color or char- 130

acter to form the stripe, it is desired to continue knitting one yarn into the fabric at all times and at certain times to throw in another yarn to form the stripe or to 5 form a reinforced portion in a fabric, this may be done with the machine of this invention by allowing one of the yarn guides, as, for instance, the yarn guide 60, to remain at all times stationary while the yarn guide 10 61 could be moved into and out of operative position with relation to the needles whenever desired by the operation of the cam 76. This result could be readily accomplished 15 by substituting for the cam 71 the collar 174 (Fig. 14) which is provided with a screw-threaded hole 175 to engage the screw 75. In such a construction it is evident that the 20 yarn guide 60 would remain stationary while the yarn guide 61 would be moved at intervals into and out of operative relation to the needles.

Instead of having a single yarn to each course extending entirely around the fabric, it is desired to reinforce the fabric throughout 25 a portion of its circumference, this may be done by running a single yarn in one course entirely around the tube of fabric and in addition thereto knitting an extra yarn into the same course for a portion of 30 the distance around the tube of fabric, the resultant fabric from such a construction being illustrated in Fig. 21. To obtain this result it is only necessary in the machine of 35 this invention to add another slide 176 to the primary cylinder, as illustrated in Fig. 4. This slide 176 will be operated to move the same nearer to or farther from the center of the primary cylinder by the pin 177 thereon engaging the cam plates 132 and 40 131, respectively, during the rotation of the primary cylinder. The slides 94 and 176 are each provided with a notch 178 and 179, respectively, whereby these slides may be pushed by hand toward the center of the 45 cylinder until the tooth 102 engages the notch 178 on the slide 94 and the tooth 180 on the spring 181 engages the notch 179 on the slide 176, at which time said slides will be entirely out of operative position as the 50 pin 133 or the pin 177 would in such case pass the cam plate 131 on the inner side thereof without engaging the same, so that either or both of these slides may be placed out of operative position by hand. By employing the two slides 94 and 176 upon the 55 primary cylinder, it will be seen that both of said slides will be set in position by means of the cam plates 131 and 132 and by the mechanism including the pattern chain 60 hereinbefore described.

In knitting the fabric illustrated in Fig. 21 in which one of each of the courses extends entirely around the fabric in a single 65 yarn course while a portion of the distance around the fabric of the same course is

knitted with two yarns, the two slides 94 and 176 are utilized and one of the yarn guides 60 remains in position at all times during the knitting operation, this being accomplished in the manner hereinbefore set forth by 70 using the collar 174. The other yarn guide 61 is operated at intervals by its cam 76 to throw its respective yarn into or out of knitting position, the same being severed by the severing mechanism each time that it is 75 thrown out of knitting position, as hereinbefore described. It will be seen that when the machine is set to knit this style of fabric, when one of the blocks on the pattern chain actuates the mechanism whereby the cam plates 131 and 132 are moved outwardly, as hereinbefore described, the slides 176 and 90 61 will be moved outwardly to engage the rotary arms 93 of the rotary member 92 and as each slide passes this rotary member it will 80 move the same ninety degrees and throw the yarn guide 61 into and out of operation alternately. The pattern chain in such a case would be provided with a series of blocks adjacent to each other on consecutive links of the pattern chain so as to hold the arm 118 in an elevated position and thus, through the mechanism hereinbefore described, to hold the cam plates 131 and 132 in their outer 95 position and at each rotation of the cylinder the two slides 94 and 176 would operate to throw the yarn guide 61 into and out of operation. The courses thus knitted in the fabric would, therefore, contain two yarns for a portion of the distance around the fabric and one yarn for the remainder of the distance, and the distance in which two yarns are 100 knitted into a single course is determined in such a case by the relative positions of the slides 94 and 176. For example, if the slides 105 94 and 176 were diametrically opposite each other each course would contain two yarns half way around the fabric and if these slides were placed ninety degrees apart, then each course would contain two yarns for 110 ninety degrees only, so that by placing said slides in different positions relatively to each other on the primary cylinder, an effect such as that illustrated in Fig. 21 could be obtained and also such as that illustrated in Fig. 22 in which longitudinal stripes 182 are 115 illustrated, these longitudinal stripes being of two yarns in each course while the spaces therebetween have a single yarn in each course. The stripes in the fabric knitted as just described on the machine of this invention may be made of any length, as illustrated in Fig. 23, thus producing rectangular spots of colored material, if desired, in which each course is knitted of two yarns while in the rest of the fabric each course is knitted of a single yarn. The termination of the double portion or stripe will be determined by the pattern chain.

When it is desired to terminate the double 120

portion or longitudinal stripe in the fabric the cam blocks upon the pattern chain will be discontinued, whereupon the arm 118 will drop downwardly and the cam plates 131 and 132 will be moved inwardly, so that as the cylinder rotates the slides 176 and 94 will be moved inwardly and out of operative position relatively to the rotary members of the yarn guide mechanisms.

19 It is desirable in the machine of this invention that the yarn guides should be capable of accurate adjustment relatively to the needles and the sinkers and that the extent of the throw of the yarn guides should 15 be capable of variation, and to secure these results the positions of the yarn guides are varied by means of the extensible links 67 and 88, and by the arms 185 and 186, and stop-screws 187 and 188. These links are 20 made in two parts connected together by turn-buckles 183 and 184, respectively, so that by turning the said turn-buckles in one direction the links 67 and 88 may be lengthened and by turning them in the opposite 25 direction said links may be shortened. When this has been done the yarn guides 60 and 61 will be lowered or raised relatively to the needles and to the sinkers and in order to change the extreme throw of the yarn guide 30 cams 71 and 76 the yarn guide rock-shafts 64 and 86 have fastened thereto arms 185 and 186, respectively, (see Figs. 3 and 18) and these arms are adapted to abut against stop-screws 187 and 188, respectively, said 35 stop-screws having screw-threaded engagement with supporting studs 189 and 190, said supporting studs, in turn, having screw-threaded engagement with the bracket 65.

When the yarn guides 60 and 61 are at 40 their lowermost position, the arms 185 and 186, respectively, abut against the stop screws 187 and 188, and this lowermost position may be varied by adjusting the screws 187 and 188 so as to regulate the distance to 45 which the yarn guides can descend and thus the relative position of the yarn guide to the sinkers and the needles will be adjusted and by this means a variation in throw of the 50 yarn guide cams will be obtained. The yarn guides 60 and 61 are moved upwardly by their respective cams 71 and 76 and are moved in the opposite direction by the 55 springs 189 and 190.

The general operation of the mechanism 55 hereinbefore specifically and to a certain extent in general described, is as follows: Assuming that it is desired to knit a fabric in which there are circumferential stripes and the courses are each knitted of a single 60 yarn and extend all around the fabric, as illustrated in Fig. 19, then the slide 176 will be pushed toward the center of the primary cylinder until the tooth 180 on the spring 181 engages the notch 179 of said 65 slide, whereupon the slide 176 will be thrown

entirely out of operation and the yarn guide mechanisms will be actuated by the slide 94. The needle cylinders are rotated in the direction of the arrow *b* (Fig. 4) by the driving shaft 19, gears 31, 32, 27, 26, 38 and 70 70 34. Each time that the cylinders are rotated the cam plate 114 engages the cam roll 113, rocking the arm 112, rock-shaft 110 and rocker arm 109 to move the ratchet 106, together with the sprocket wheel 104, forward one tooth, thus moving the pattern chain 103 forward in the direction of the arrow *c* (Fig. 10). The yarn 138 is fed to the primary needles 39 by the yarn guide 60 and is fed in between said needles by the 80 sinkers 50 and 51 on the sinker wheel 52 in a manner well known to those skilled in this art. The usual operation of machines of this class is then followed in knitting a yarn into a fabric, the upper needles 44 co-operating with the needles 39 and the pressers 58 and 59, together with the several needle cams, in the usual well known manner. As the pattern chain moves along step by step it is finally brought to the point where one 90 of the cam blocks 134 engages the free end of the arm 118, lifting said arm sufficiently to rock the same, together with the rock-shaft 119 to which it is fastened, thus rocking the arm 121 and, through the link 122, 95 rocker arm 123 and link 125, moving the slide 126 outwardly and thus moving the cam plates 131 and 132 outwardly from the center of the needle cylinders, so that as the needle cylinders revolve in the direction of 100 the arrow *b*, the pin 133 on the slide 94 will engage the cam 131 and said slide be moved outwardly, so that its outer end will assume the position *a* (Fig. 4). As the cylinders 105 continue to rotate, the slide 94 will then engage one of the arms on the rotary member 92 of the feed A and rotate said rotary member ninety degrees, thus rotating the cams 71 and 76 ninety degrees and causing the arm 70 to be rocked by the cam plate 73 110 outwardly from the cam 71. This will move the arm 68 downwardly, pulling downwardly upon the link 67, rocking the arm 66 and rock-shaft 64 to raise the yarn guide 60. 115 The yarn guides during the different movements of the mechanism hereinbefore described occupy four positions indicated as positions *d*, *c*, *f* and *g* in Figs. 16 and 17. During the operation of the machine, when one of the yarn guides is in operative position and the other in inoperative position, said yarn guides will occupy the positions *e* and *f*, as illustrated in full lines (Fig. 17). At that time the yarn guide occupying the position *f* is feeding yarn to the sinkers and needles, while the yarn guide occupying the position *e* is out of operative position and the yarn is hanging down with its free end lying along the tops of the sinkers. When the change in position of the yarn 120 125 130

guides hereinbefore described occurs the yarn guide occupying the position *f* is carried upwardly to the position *d*, thus carrying the yarn between the cutters ready to be cut. Immediately after arriving at the position *d*, the yarn guide will drop to the position *e* and at this time the severing of the yarn will take place. While this operation is taking place with one of the yarn guides, the other yarn guide will move from the position *c* to the position *g* and this carries the free end of the yarn down into the position illustrated in Fig. 16, so that it will be engaged by the projection 173 on the 15 sinker 51 and held down in the path of the sinkers adjacent thereto. As soon as the yarn has been engaged by said projection 173 and carried into the path of the sinkers adjacent thereto, the yarn guide will rise 20 from the position *g* to the position *f* and the yarn will then be taken by all of the sinkers 50 and 51 and fed to the needles in the usual manner. These different positions of the 25 yarn guides are obtained by reason of the different throws of the yarn guide cam plates 73 and 74, 79 and 80, said cam plates being formed, as hereinbefore set forth, to first raise the yarn guide to the position *d* and then drop it to the position *e*, the purpose of this throw being to insure the yarn which is thrown out of operation being lifted out of the path of the needles and the returning slight movement of the yarn guide to the position *c* is for the purpose of giving 30 the yarn slack while it is being cut by the cutters 151 and 152.

It will be understood that after the yarn has been severed the loose end thereof will fall approximately into the position illustrated in Fig. 17, the free end of the yarn falling over the ends of the sinkers. If, when the yarn has been severed as hereinbefore set forth, the free end should fly upwardly instead of falling downwardly, then 45 said free end would strike the yarn guard 171, as illustrated in dotted lines (Fig. 17), which would keep said free end from being thrown over the yarn guide 60 or 61, as the case might be, and subsequently the free end 50 of the yarn would drop down into the position illustrated in Fig. 17 and lie along the tops of the sinkers.

It will be understood that one of the features of novelty of this invention is the finger 173 cooperating with the yarn guide from which the free end of the yarn leads to lay said free end in the path of the sinkers and to thus cause the same to be guided with precision and accuracy between the 60 needles of the primary cylinder. Each time that the yarn guides change position, one yarn is cut off by the respective sets of cutters for the particular feed to which it belongs. The operation of the cutting mechanism has been hereinbefore fully described.

It will be understood that when one of the cam blocks, say 134, has moved the cam plates 131 and 132 into position so that the slide 94 is moved outwardly to engage the arms 93 on the rotary member 92 and change the position of the yarn guides, these cam plates, through the mechanism which is actuated by the cams 71 and 76, with said yarn guides, will remain as thus positioned after the block 134 has passed the arm 118, by reason of the fact that said arm 118 will drop onto the pattern chain 103, and thus the cams 131 and 132 will be moved back to their normal position by the spring 129 and the slide 94 will then be moved back to the position illustrated in Fig. 4 so as not to engage any of the rotary members 92, and until it does engage said rotary members again the respective yarn guides of each feed will remain in the position to which they were moved when the slide 94 was moved outwardly, as just described. Thus the number of circumferential stripes and the width of said stripes may be determined by the pattern chain and the particular 80 yarns fed to the stripe at each rotation of the cylinders will be determined by the height of the cam blocks 134 or 135, for the reason that the slide 94, as hereinbefore described, will be set at different distances 90 radially from the center of the needle cylinders and will thus operate the rotatable members 92 of the different feeds or not according to the distance to which said slide is moved radially with relation to the needle cylinders. For example, when the slide 94 is in the position illustrated in Fig. 4 it will not engage either of the rotatable members in the feed A or the feed B. When it is in the position where the tooth 102 enters the 100 notch 99, then the slide is in the position marked *a* (Fig. 4) and said slide will engage the rotatable member 92 of the feed A, but will not engage the rotatable member 92 of the feed B, as said rotatable member is located a greater distance from the center of the needle cylinders than the rotatable member of the feed A, but when said slide 94 is advanced until the tooth 102 enters the notch 100, then said slide will be in the position marked *b* (Fig. 4) and will engage both the 110 rotatable member 92 of the feed A and the rotatable member 92 of the feed B and, therefore, the yarn guides, in both 115 of these feeds in the latter case will be operated to change the feed of the yarn to the needles.

It is evident that a variety of combinations may be obtained by the mechanism hereinbefore set forth: First, the yarns from the two yarn guides may be alternately fed to the needles, one yarn being fed to the needles by one yarn guide and then said yarn guide moved out of operative relation to the needles, while the other yarn guide is 130

brought into operative relation thereto, the yarn being cut off from each of the yarn guides which is out of operation alternately, and in this case the fabric would be knit as of one yarn and then of another, as illustrated in Figs. 19 and 20, producing circumferential stripes. Second, one of the yarns may be continually knitted into the fabric, as hereinbefore described, by leaving 10 one of the yarn guides stationary and causing the other to be moved into and out of operative relation to the needles, as illustrated in Fig. 21, producing a circular fabric with portions thereof of a double 15 thickness and other portions of a single thickness. Third, by the use of different heights of cam blocks the yarn guides may be operated for one feed to change and not for another. Fourth, either one of the yarn 20 guides or both may be left in operative position for any desired length of time or for any desired length of fabric being knitted by throwing out the instrumentalities connecting the pattern chain with the cam for 25 operating the slide 94—that is, by throwing out of operation the arm 118 (Fig. 10). Fifth, one of the yarn guides may be left in operative position while the other yarn 30 guide is thrown into and out of operative position alternately in the same course, thus producing a reinforced portion of the fabric illustrated in Fig. 21 or the longitudinal stripes or reinforced fabric illustrated in Fig. 22, this fabric being obtained, as hereinbefore described, by the use of more than 35 one slide movable with the primary cylinder and operating the yarn guide mechanisms.

Having thus described my invention, what I claim and desire by Letters Patent to secure is:

1. A feed mechanism for a circular knitting machine having, in combination, a rotary member, a yarn guide adapted to feed yarn to the needles of said knitting machine, mechanism adapted to move said yarn guide into operative position relatively to said needles, said mechanism being adapted to hold said yarn guide in said position, means on said rotary member adapted to actuate 45 said yarn guide actuating mechanism and mechanism adapted to move said last-named means into and out of operative position on said rotary member.

2. A feed mechanism for a circular knitting machine having, in combination, a rotary member, a yarn guide adapted to feed yarn to the needles of said knitting machine, mechanism, including a stationary support, outside said rotary member adapted to move 55 said yarn guide into and out of operative position relatively to said needle, means on said rotary member adapted to actuate said yarn guide mechanism and mechanism adapted to move said last-named means to different positions relatively to the median

axial line of said rotary member and into and out of operative position.

3. A feed mechanism for a circular knitting machine, having, in combination, a rotary member, a sinker wheel with sinkers, a 60 yarn guide, means adapted to sever the yarn between the needles of said knitting machine and said yarn guide, said means adapted to drop the free end of said yarn when severed and leave said free end floating on the upper 65 edges of said sinkers, said sinker wheel being located between said yarn guide and severing mechanism, mechanism adapted to move said yarn guide into and out of operative position relatively to said needles and sinker 70 wheel whereby the free end of said yarn, when said yarn guide is in operative position, may be laid across the ends of said sinkers and fed to said needles by said sinker wheel, and means movable with said 75 rotary member adapted to actuate said yarn guide actuating mechanism and said severing mechanism.

4. A feed mechanism for a circular knitting machine having, in combination, a rotary member, a yarn guide adapted to feed yarn to the needles of said knitting machine, mechanism adapted to move said yarn guide into and out of operative position relatively to said needles, said mechanism adapted to 80 hold said yarn guide in said positions, means adapted to sever said yarn between said needles and said yarn guide, means on said 85 rotary member adapted to actuate said yarn guide actuating mechanism and said severing mechanism and mechanism adapted to move said last-named means into and out of operative position on said rotary member.

5. A feed mechanism for a circular knitting machine having, in combination, a rotary member, a yarn guide adapted to feed yarn to the needles of said knitting machine, a cam, mechanism actuated by said cam adapted to move said yarn guide into and out of operative position relatively to said 90 needles, said cam adapted to hold said yarn guide in said positions, a plurality of arms fast to said cam, means on said rotary member adapted to engage one of said arms at a time and rotate said cam to alternately move 95 said yarn guide into and out of operative position and mechanism adapted to move said arm engaging means into and out of operative position on said rotary member.

6. A feed mechanism for circular knitting 100 machines having, in combination, a rotary member, a yarn guide, a cam, mechanism actuated by said cam adapted to move said yarn guide into and out of operative position relatively to the needles of said knitting machine, a plurality of arms fast to said cam; means movable with said rotary member adapted to engage one of said arms at a 105 time and rotate said cam to alternately move said yarn guide into and out of operative 110 position.

position relatively to said needles, mechanism adapted to move said arm engaging means into and out of operative position and instrumentalities actuated by said arm engaging means adapted to sever the yarn between said yarn guide and said needles.

7. A feed mechanism for a circular knitting machine having, in combination, a rotary member, a yarn guide, mechanism adapted to move said yarn guide into and out of operative position relatively to the needles of said knitting machine, a slide movable radially on said rotary member, said slide adapted to actuate said yarn guide actuating mechanism and mechanism, including a pattern chain with cams thereon, adapted to move said slide into and out of operative position.

8. A feed mechanism for a knitting machine having, in combination, a rotary member, a yarn guide, mechanism adapted to move said yarn guide into and out of operative position relatively to the needles of said knitting machine, a slide movable with said rotary member adapted to actuate said yarn guide actuating mechanism, a cam adapted to be engaged by said slide to move said slide radially on said rotary member, and mechanism, including a pattern chain with projections thereon, adapted to move said cam radially relatively to said rotary member, whereby said slide may be moved into and out of operative position relatively to said yarn guide actuating mechanism.

9. A feed mechanism for a circular knitting machine having, in combination, a rotary member, a yarn guide, mechanism adapted to move said yarn guide into and out of operative position relatively to the needles of said knitting machine, a slide on said rotary member adapted to actuate said yarn guide actuating mechanism, a cam adapted to be engaged by said slide to move said slide radially on said rotary member, mechanism, including a pattern chain with projections thereon, adapted to move said cam radially relatively to said rotary member, whereby said slide may be moved into and out of operative position relatively to said yarn guide actuating mechanism and mechanism, including a lever, adapted to sever the yarn between said yarn guide and said needles, said lever adapted to be engaged by said slide to rock the same and actuate said yarn severing mechanism.

10. A feed mechanism for a circular knitting machine having, in combination, a rotary member, a sinker wheel with sinkers, a pair of yarn guides, means adapted to alternately sever yarn leading from each of said yarn guides between the needles of said knitting machine and said yarn guides, said severing means adapted to drop the free ends of said yarns, when severed, and leave said free ends floating on the upper edges

of said sinkers, said sinker wheel being located between said yarn guides and severing mechanism, mechanism adapted to move each of said yarn guides, respectively, into and out of operative position relatively to 70 said needles, and said sinker wheel and to carry the free ends of said yarn across the outer ends of said sinkers, whereby the free ends of said yarns may be fed to said needles by said sinker wheel, and means movable with said rotary member adapted to actuate said yarn guide actuating mechanism and said severing mechanism.

11. A feed mechanism for a circular knitting machine having, in combination, a rotary member, a sinker wheel with sinkers, a yarn guide, means adapted to sever the yarn between the needles of said knitting machine and said yarn guide, said means adapted to drop the free end of said yarn 80 when severed and leave said free end floating on the upper edges of said sinkers, said sinker wheel being located between said yarn guide and severing mechanism, mechanism adapted to move said yarn guide into 85 and out of operative position relatively to said needles and sinker wheel whereby the free end of said yarn, when said yarn guide is in operative position, may be laid across the ends of said sinkers and fed to said needles by said sinker wheel, said sinkers each having a projection on the outer end thereof extending radially beyond the outer ends of the sinkers adjacent thereto and adapted to engage the free end of said severed yarn 90 and hold said free end in line with the ends of the sinkers adjacent thereto, and means movable with said rotary member adapted to actuate said yarn guide actuating mechanism and said severing mechanism.

12. A feed mechanism for a circular knitting machine having, in combination, a rotary member, a plurality of pairs of yarn guides arranged around said rotary member, the yarn guides of each of said pairs 100 of yarn guides adapted to guide yarn to the needles of said knitting machine, mechanism adapted to move each of the yarn guides of each of said pairs, respectively, into and out of operative position alternately relatively to said needles, said mechanism adapted to hold said yarn guides in said positions, means on said rotary member adapted to actuate all of said yarn guide mechanisms, and mechanism adapted 110 to move said last-named means into operative position relatively to a portion of said yarn guide mechanisms and out of operative position relatively to all of said yarn guide mechanisms.

13. A feed mechanism for a circular knitting machine having, in combination, a rotary member, a plurality of pairs of yarn guides arranged around said rotary member, the yarn guides of each of said pairs of 120

yarn guides adapted to guide yarn to the needles of said knitting machine, mechanism adapted to move each of the yarn guides of each of said pairs, respectively, into and out of operative position alternately relatively to said needles, said mechanism adapted to hold said yarn guides in said positions, a slide on said rotary member adapted to actuate all of said yarn guide mechanisms, and mechanism, including a pattern chain with cams thereon, adapted to move said slide into and out of operative position relatively to all of said yarn guide mechanisms.

14. A feed mechanism for a circular knitting machine having, in combination, a rotary member, a plurality of pairs of yarn guides arranged around said rotary member, the yarn guides of each of said pairs of yarn guides adapted to guide yarn to the needles of said knitting machine, mechanism adapted to move each of the yarn guides of each of said pairs, respectively, into and out of operative position alternately relatively to said needles, said mechanism adapted to hold said yarn guides in said positions, a slide on said rotary member and movable radially thereon, a cam adapted to be engaged by said slide to move said slide radially relatively to said rotary member and mechanism, including a pattern chain with projections of different heights thereon, adapted to move said cam to different positions radially relatively to said rotary member, whereby said slide may be moved into and out of operative position relatively to all of said yarn guide mechanisms and also whereby said slide may be moved into and out of operative position relatively to a portion of said yarn guide mechanisms.

15. A feed mechanism for a circular knitting machine having, in combination, a rotary member, a pair of yarn guides, each of said yarn guides adapted to guide yarn to the needles of said knitting machine, mechanism adapted to move one of said yarn guides into and out of operative position relatively to said needles, said mechanism adapted to hold said last-named yarn guide in said positions, means on said rotary member adapted to actuate said yarn guide mechanism and mechanism adapted to move said last-named means on said rotary member into and out of operative position.

16. A feed mechanism for a circular knitting machine having, in combination, a rotary member, a sinker wheel and sinkers, a yarn guide adapted to guide yarn to said sinkers and to the needles of said knitting machine, mechanism adapted to move said yarn guide into operative position relatively to said needles, with the free end of said yarn extending across the ends of said sinkers and thence along the upper edges thereof, said mechanism adapted to hold said

yarn guide in said position, means on said rotary member adapted to actuate said yarn guide actuating mechanism and mechanism adapted to move said last-named means on said movable member into and out of operative position.

17. A feed mechanism for a circular knitting machine having, in combination, a rotary member, a sinker wheel and sinkers, a yarn guide adapted to guide yarn to said sinkers and to the needles of said knitting machine, mechanism adapted to move said yarn guide into and out of operative position relatively to said needles with the free end of said yarn, when said yarn guide is in operative position, extending across the ends of said sinkers and thence along the upper edges thereof, said mechanism adapted to hold said yarn guide in said positions, means on said rotary member adapted to actuate said yarn guide actuating mechanism and mechanism, including a pattern chain with cams thereon, adapted to move said last-named means into and out of operative position.

18. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, means movable with said driving member adapted to actuate said yarn guide actuating mechanism, and instrumentalities, including a pattern chain with cams thereon, adapted to move said last-named means into and out of operative position.

19. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, means on said driving member adapted to actuate said yarn guide actuating mechanism, instrumentalities, including a pattern chain with cams thereon, adapted to move said last-named means into and out of operative position and means carried by said driving member adapted to operate said pattern chain instrumentalities.

20. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, means on said driving member adapted to actuate said yarn guide actuating mechanism and

instrumentalities, including a pattern chain with cams thereon, a rock-shaft and a rocker-arm fast to said rock-shaft and adapted to be engaged by said pattern chain cams, adapted to move said last-named means into and out of operative position.

21. A feed mechanism for a circular knitting machine having, in combination, a driving member, a yarn guide adapted to guide yarn to the needles of said knitting machine, mechanism adapted to move said yarn guide into and out of operative position relatively to said needles, means on said driving member adapted to actuate said yarn guide actuating mechanism, instrumentalities, including a pattern chain with cams thereon, a rock-shaft and a rocker arm and means to fasten said rocker arm to said rock-shaft in different positions relatively thereto whereby said rocker arm may be set so as to be engaged by said pattern chain cams and also may be set so as to be cleared by said cams, whereby said first-named means may be respectively moved into and out of operative position and left in either of said positions while said pattern chain with its cams continues in operation.

22. A feed mechanism for a circular knitting machine having, in combination, a driving member, a yarn guide adapted to guide yarn to the needles of said knitting machine, mechanism adapted to move said yarn guide into and out of operative position relatively to said needles, means on said driving member adapted to actuate said yarn guide actuating mechanism, and instrumentalities, including a pattern chain with cams thereon and a movable member adapted to be positioned so as to be engaged by said pattern chain cams, said movable member also adapted to be positioned so as to be cleared by said cams, whereby said last-named means may be respectively moved into and out of operative position and left in either of said positions while said pattern chain with its cams continues in operation.

23. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, mechanism adapted to sever said yarn between said needles and said yarn guide, means on said driving member adapted to actuate said yarn guide actuating mechanism and said severing mechanism, mechanism adapted to move said last-named means into and out of operative position and means adapted to lock said last-named means in either of said positions.

24. A feed mechanism for a circular

knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, a slide on said driving member adapted to actuate said yarn guide actuating mechanism, mechanism adapted to move said slide on said driving member into and out of operative position and means to lock said slide in either of said positions.

25. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, a slide on said driving member adapted to actuate said yarn guide actuating mechanism, mechanism adapted to move said slide on said driving member into and out of operative position, said slide being provided with a plurality of notches, and a spring adapted to engage said slide within said notches whereby said slide may be locked in either of said positions.

26. A feed mechanism for a circular knitting machine having, in combination, a driving member, a yarn guide adapted to guide yarn to the needles of said knitting machine, means adapted to move said yarn guide into and out of operative position relatively to said needles, means adapted to sever said yarn between said needles and said yarn guide, a rotary sinker wheel, a plurality of sinkers supported on said sinker wheel and adapted to be moved in and out between said needles, a plurality of said sinkers each having a projection on the outer end thereof extending radially beyond the outer ends of the sinkers adjacent thereto and adapted to engage the free end of said severed yarn and hold said free end in line with the ends of the sinkers adjacent thereto.

27. A feed mechanism for a circular knitting machine having, in combination, a driving member, a yarn guide adapted to guide yarn to the needles of said knitting machine, means adapted to move said yarn guide into and out of operative position relatively to said needles, means adapted to sever said yarn between said needles and said yarn guide, a sinker carrier, a plurality of sinkers supported upon said carrier and adapted to be moved in and out between said needles, a plurality of said sinkers each having a projection on the outer end thereof extending beyond the outer ends of the sinkers adjacent thereto and adapted to engage the free end of said severed yarn and hold said free

end in line with the ends of the sinkers adjacent thereto.

28. A feed mechanism for a circular knitting machine having, in combination, a rotary member, a yarn guide adapted to guide yarn to the needles of said knitting machine, a yarn cutter located intermediate said yarn guide and needles and above said needles, mechanism adapted to move said
- 10 yarn guide upwardly and adapted to hold said yarn guide in said elevated position, whereby the yarn leading from said yarn guide to said needles is carried into position to be severed by said yarn cutter,
- 15 means on said rotary member adapted to actuate said yarn guide mechanism and said cutter, and mechanism adapted to move said last-named means on its rotary member into and out of operative position.
- 20 29. A feed mechanism for a circular knitting machine having, in combination, a rotary member, a yarn guide adapted to guide yarn to the needles of said knitting machine, a yarn cutter located intermediate said yarn
- 25 guide and needles and above said needles and comprising a stationary blade and a pivoted blade adapted to swing about a horizontal pivot and projecting downwardly from said pivot, mechanism adapted to rock
- 30 said pivoted blade on its pivot, mechanism adapted to move said yarn guide upwardly and adapted to hold said yarn guide in said elevated position, whereby the yarn leading from said yarn guide to said needles may be
- 35 carried between said cutter blades and may be severed thereby, means on said rotary member adapted to actuate said yarn guide mechanism and cutter mechanism and mechanism adapted to move said last-named
- 40 means on said rotary member into and out of operative position.
30. A feed mechanism for circular knitting machines having, in combination, a driving member, a yarn guide, a sinker
- 45 wheel with sinkers adapted to guide yarn to the needles of said knitting machine, means adapted to move said yarn guide into and out of operative position relatively to said needles, means adapted to sever said
- 50 yarn between said needles and said yarn guide and a guard adjacent to said guide and projecting above and transversely of said needles and sinker wheel adapted to engage the free end of said yarn after the
- 55 same has been severed to cause said free end to fall on the upper edges of said sinkers.
31. A feed mechanism for circular knitting machines having, in combination, a driving member, a series of sinkers, a sup-
- 60 port therefor, means to move said sinkers in and out between the needles of said knitting machine, a yarn guide adapted to guide yarn to said needles, means adapted to move said yarn guide into and out of operative
- 65 position relatively to said needles, a sup-

port for said needles adjacent to said sinkers and on the opposite side of said needles therefrom, means adapted to sever said yarn between said needles and yarn guide and a guard adjacent to said guide mounted

70 on said needle support and extending therefrom transversely of and above said needles and said sinker wheel and adapted to engage the free end of said yarn after the same has been severed to cause said free end to fall

75 on the upper edges of said sinkers.

32. A feed mechanism for a circular spring needle knitting machine having, in combination, a rotary member, a sinker wheel and sinkers, a pair of yarn guides, each adapted to coöperate with said sinkers to guide yarn to the spring needles of said knitting machine, mechanism adapted to move one of said yarn guides into and out of operative position relatively to said needles and sinkers, said mechanism adapted to hold said yarn guide in said positions and a plurality of independent means on said rotary member adapted to alternately actuate said yarn guide mechanism to move its respective

80 yarn guide into and out of said operative position.

33. A feed mechanism for a circular knitting machine having, in combination, a rotary member, a pair of yarn guides, each adapted to guide yarn to the needles of said knitting machine, mechanism adapted to move one of said yarn guides into and out of operative position relatively to the needles of said knitting machine and to hold

85 said yarn guides in said positions, a plurality of independent means on said rotary member adapted to alternately actuate said yarn guide mechanism to move its respective yarn guide into and out of said operative

90 position and mechanism adapted to move said last named means into and out of operative position.

34. A feed mechanism for a circular knitting machine having, in combination, a rotary member, a sinker wheel, a pair of yarn guides, each adapted to guide yarn to the needles of said knitting machine, mechanism adapted to move one of said yarn guides into and out of operative position relatively to

110 said needles, a cutting mechanism adapted to sever the yarn leading from said movable yarn guide to said sinker wheel and needles between said needles and said movable yarn guide, said cutting mechanism adapted to

115 allow the free end of said yarn to fall on the upper edges of said sinkers, a plurality of said sinkers each having a projection on the outer end thereof extending radially beyond the outer ends of the sinkers adjacent thereto and adapted to engage the floating free end of said severed yarn and hold said free end in line with the ends of the sinkers adjacent thereto and a plurality of independent means movable with said rotary mem-

120

ber adapted to alternately actuate said yarn guide mechanism to move its respective yarn guide into and out of operative position, said independent means adapted to operate said 5 severing mechanism.

35. A feed mechanism for a circular spring needle knitting machine having, in combination, a rotary member, a sinker wheel and sinkers, a pair of yarn guides, 10 each adapted to coöperate with said sinkers to guide yarn to the spring needles of said knitting machine, mechanism adapted to move each of said yarn guides respectively into and out of operative position alternately 15 relatively to said needles and sinkers, said mechanism adapted to hold said yarn guides in said positions and a plurality of independent means on said rotary member adapted to alternately actuate said yarn 20 guide mechanisms to move said yarn guides into and out of operation during each rotation of said rotary member.

36. A feed mechanism for a circular knitting machine having, in combination, a rotary member, a pair of yarn guides, each adapted to guide yarn to the needles of 25 said knitting machine, mechanism adapted to move each of said yarn guides respectively into and out of operative position 30 alternately relatively to said needles and adapted to hold said yarn guides in their respective positions, a plurality of independent means movable with said rotary member adapted to alternately actuate said 35 yarn guide mechanisms to move said yarn guides into and out of operation during each rotation of said rotary member and mechanism adapted to move said last-named means into and out of operative position.

37. A feed mechanism for a circular knitting machine having, in combination, a rotary member, a plurality of pairs of yarn guides arranged around said rotary member, each of said yarn guides adapted to guide yarn to the needles of said knitting machine, mechanism, including a stationary support, adapted to move each of the yarn guides of each of said pairs, respectively, 45 into and out of position alternately relatively to said needles, said mechanism adapted to hold said yarn guides in said positions, said yarn guide actuating mechanisms located at different distances from said rotary member, means on said rotary member adapted to actuate all of said yarn guide actuating mechanisms and mechanism adapted to move said last-named means into operative position relatively to a predetermined number of said yarn guide actuating mechanisms and out of operative position relatively to all of said yarn guide actuating mechanisms.

38. A circular knitting machine having, 50 in combination, a needle cylinder, a set of

needles thereon, mechanism adapted to impart a rotary motion to said cylinder, a sinker wheel with sinkers, a yarn guide, means adapted to sever the yarn between said needles and yarn guide and drop the 70 free end of said yarn, when severed, on the upper edges of said sinkers, said sinker wheel being located between said yarn guide and severing mechanism, mechanism adapted to move said yarn guide into and out of 75 operative position relatively to said needles and sinker wheel, whereby the free end of said yarn may be fed to said needles by said sinker wheel, adjustable means adapted to change the position of said yarn guide relatively to said sinkers, other means adapted to change the throw of said yarn guide, and means movable with said needle cylinder adapted to actuate said yarn guide actuating mechanism and said severing mechanism. 80

39. A circular knitting machine having, in combination, a needle cylinder, a set of needles thereon, a sinker wheel with sinkers, a yarn guide, means adapted to sever the 85 yarn between said needles and yarn guide and drop the free end of said yarn, when severed, on the upper edges of said sinkers, said sinker wheel being located between said yarn guide and said severing mechanism and mechanism adapted to move said yarn guide into and out of operative position relatively to said needles and sinker wheel, whereby the free end of said yarn may be fed to said needles by said sinker wheel. 90

40. A feed mechanism for a circular knitting machine having, in combination, a rotary member, a yarn guide, mechanism adapted to move said yarn guide into and out of operative position relatively to the 105 needles of said knitting machine, a slide movable radially on said rotary member, said slide adapted to actuate said yarn guide actuating mechanism and mechanism, including a pattern member with projections 110 thereon, adapted to move said slide into and out of operative position.

41. A feed mechanism for a knitting machine having, in combination, a rotary member, a yarn guide, mechanism adapted to 115 move said yarn guide into and out of operative position relatively to the needles of said knitting machine, a slide movable with said rotary member adapted to actuate said yarn guide actuating mechanism, a cam 120 adapted to be engaged by said slide to move said slide radially on said rotary member, and mechanism, including a pattern member with projections thereon, adapted to move said cam radially relatively said rotary 125 member, whereby said slide may be moved into and out of operative position relatively to said yarn guide actuating mechanism.

42. A feed mechanism for a circular knitting machine having, in combination, a driv-

ing member, a yarn guide adapted to guide yarn to the needles of said knitting machine, mechanism adapted to move said yarn guide into and out of operative position relatively to said needles, said mechanism adapted to hold said yarn guide in said positions, means movable with said driving member adapted to actuate said yarn guide actuating mechanism, and instrumentalities, including a pattern member with projections thereon, adapted to move said last-named means into and out of operative position.

43. A feed mechanism for a circular knitting machine having, in combination, a driving member, a yarn guide adapted to guide yarn to the needles of said knitting machine, mechanism adapted to move said yarn guide into and out of operative position relatively to said needles, said mechanism adapted to hold said yarn guide in said positions, means on said driving member adapted to actuate said yarn guide actuating mechanism, and instrumentalities adapted to move said last-named means into and out of operative position, said instrumentalities including a pattern member with projections thereon, a rock shaft and a rocker arm fast to said rock shaft and adapted to be engaged by said pattern projections.

44. In combination, in a knitting machine striping means including a pair of yarn guide fingers pivotally supported, a yarn cutter, said parts being mounted on the fixed frame, a contact member rotating with the machine, a pattern controlled device on the fixed frame for setting said contact in operative or inoperative position, a pair of contacts on the fixed frame one for the yarn guide and one for the cutter, and connections extending up from the said contacts and thence inwardly to the yarn fingers and cutters for operating the same, substantially as described.

45. In combination, in a knitting machine, a plurality of striping mechanisms, each including a pair of yarn fingers and a yarn cutter, mounted on the fixed frame, a series of pairs of contacts on the fixed frame, one for each striping mechanism, connections from a contact of each pair to the yarn fingers of the appropriate striping mechanism and independent of the other yarn finger connections, one connection from the other contact of each pair to one of the cutters, and independent of the other cutter connections, a shiftable contact on a rotary part of the machine for operating all the said connections successively by striking their contacts and means for moving the said shiftable contact substantially as described.

46. In combination in a circular knitting machine, a plurality of stripers including movable yarn feed fingers, a rotary member for operating them, said member having movement circumferentially about the axis

of the knitting head and operating means for the said circumferentially movable member comprising contact means in part carried by a rotary part of the knitting machine and in part supported by a fixed portion of said machine, substantially as described.

47. In combination in a circular knitting machine, yarn changing means, a pair of star wheels for operating the same, a pair of contacts traveling with a moving part of the machine to operate in succession upon each of the star wheels, a cam for determining times of action of the contacts upon the star wheels and pattern means for moving the cam, substantially as described.

48. In combination in a circular knitting machine, yarn changing means, a pair of star wheels on horizontal shafts, a pair of pins traveling with a rotary part of the machine for operating each of the star wheels twice during the passage of the pins, and operating means extending from the star wheels to the yarn changing means, substantially as described, and means located on a stationary base to move said pins into and out of operative position.

49. In combination in a circular knitting machine, yarn changing means, a pair of star wheels on horizontal shafts, a pair of pins traveling with a rotary part of the machine for operating each of the star wheels twice during the passage of the pins and operating means from the star wheels to the yarn changing means, said operating means being actuated from the horizontal shafts of the star wheels, substantially as described, and means located on a stationary base to move said pins into and out of operative position.

50. In combination in a circular knitting machine, a yarn changing mechanism comprising a pair of yarn feed fingers and a yarn cutter, a revolving ring, a fixed base portion surrounding said ring, contact means located in part on said ring and in part on the fixed base and connections extending from the contact means of the fixed base to the yarn feed fingers and the yarn cutter for operating the same, substantially as described, and means located on said fixed base constructed and arranged to move the contact means on said revolving ring into and out of operative position.

51. In combination in a circular knitting machine, a yarn changing mechanism comprising yarn feed fingers and a yarn cutter, a pair of star wheels in a fixed part of the machine, a pair of contact means on a revolving part of the machine for operating the star wheels and connections extending vertically and thence radially inward for operating the yarn feed fingers and the yarn cutter, substantially as described, and means located on said fixed part of the machine

constructed and arranged to move the contact means on said revolving part of the machine into and out of operative position.

52. A feed mechanism for a circular knitting machine having, in combination, a rotary member, a pair of yarn guides in a single feed, each adapted to guide yarn to the needles of said knitting machine, mechanism adapted to move each of said yarn guides, respectively, into and out of operative position relatively to said needles, means movable with said rotary member adapted to actuate said yarn guide mechanism to move said yarn guides alternately into and out of operation, and mechanism adapted to move said last named means into and out of operative position.

53. A feed mechanism for a circular knitting machine having, in combination, a rotary member, a pair of yarn guides, each adapted to guide yarn to the needles of said knitting machine, mechanism adapted to move each of said yarn guides, respectively, into and out of operative position relatively to said needles and adapted to hold said yarn guides in their respective positions, means movable with said rotary member adapted to actuate said yarn guide mechanism to move said yarn guides alternately into and out of operation, and mechanism adapted to move said last named means into and out of operative position.

54. In combination, in a knitting machine, rotary needle carrier and nonrotary cams, a series of striping mechanisms fixed at different points about the needle circle and embodying a movable thread guide and means to hold said thread guide in operative position, an operating connection for each of said striping mechanisms, said connections being independent of each other, each of said connections including contact means on the fixed frame, a contact device on a rotary part of the machine to operate the contact means of the several striping mechanisms in succession, and means effecting a shifting movement of the rotating contact device to hit or miss the contact means, substantially as described.

55. In combination, in a knitting machine, a rotary needle cylinder, a plurality of yarn changers disposed at different points about the needle cylinder, each yarn changer including a pair of yarn guide fingers, with means for operating them, and a yarn cutter, a series of pairs of contacts on the fixed frame, one pair for each yarn changer, pairs of rods extending upwardly from said contacts, bell cranks connected with said rods, and rods extending substantially radially inward and connected respectively to the yarn finger operating means and the yarn cutter and independent of the rods leading to the other yarn fingers and the other cutters, substantially as described.

56. A feed mechanism for a circular knitting machine having, in combination, a rotary member, a plurality of pairs of yarn guides arranged around said rotary member, the yarn guides of each of said pairs of yarn guides adapted to guide yarn to the needles of said knitting machine, mechanism adapted to move each of the yarn guides of each of said pairs, respectively, into and out of operative position alternately relatively to said needles, means on said rotary member adapted to actuate all of said yarn guide mechanisms and mechanism adapted to move said last-named means into and out of operative position on said rotary member.

57. A feed mechanism for a circular knitting machine having, in combination, a rotary member, a plurality of pairs of pivotally supported yarn guides arranged around said rotary member, the yarn guides of each of said pairs of yarn guides adapted to guide yarn to the needles of said knitting machine, mechanism adapted to move each of the yarn guides of each of said pairs, respectively, into and out of operative position alternately relatively to said needles, means on said rotary member adapted to actuate all of said yarn guide mechanisms and mechanism adapted to move said last-named means into and out of operative position on said rotary member, said yarn guide mechanism adapted to hold said yarn guides in said positions.

58. A feed mechanism for a circular knitting machine having, in combination, a rotary member, a pair of yarn guides, each of said yarn guides adapted to guide yarn to the needles of said knitting machine, mechanism adapted to alternately move said yarn guides into and out of operative position relatively to said needles, said mechanism adapted to hold said yarn guides in said positions, means on said rotary member adapted to actuate said yarn guide mechanism and manually operable mechanism adapted to move said last-named means on said rotary member into and out of operative position.

59. A feed mechanism for a circular knitting machine having, in combination, a rotary member, a pair of yarn guides each adapted to guide yarn to the needles of said knitting machine, mechanism on a stationary base adapted to move each of said yarn guides, respectively, into and out of operative position relatively to said needles, means on said rotary member movable with and relatively thereto adapted to actuate said yarn guide mechanism to move said yarn guides alternately into and out of operation and mechanism adapted to move said last-named means relatively to said rotary member and into and out of operative position relatively to said yarn guide mechanism.

60. A feed mechanism for a circular knitting machine having, in combination, a rotary member, a yarn guide adapted to feed yarn to the needles of said knitting machine, mechanism on a stationary base adapted to move said yarn guide into operative position relatively to said needles, said mechanism being adapted to hold said yarn guide in said position, means on said rotary member adapted to actuate said yarn guide actuating mechanism and mechanism adapted to move said last-named means into and out of operative position on said rotary member.
61. A feed mechanism for a circular knitting machine having, in combination, a rotary member, a yarn guide adapted to feed yarn to the needles of said knitting machine, mechanism on a stationary base adapted to move said yarn guide into operative position relatively to said needles, said mechanism being adapted to hold said yarn guide in said position, means on said rotary member adapted to actuate said yarn guide actuating mechanism and mechanism on a stationary base adapted to move said last-named means into and out of operative position on said rotary member.
62. A feed mechanism for a circular knitting machine having, in combination, a rotary member, a pair of yarn guides, each of said yarn guides adapted to guide yarn to the needles of said knitting machine, mechanism on a stationary base adapted to move one of said yarn guides into and out of operative position relatively to said needles, said mechanism adapted to hold said last-named yarn guide in said positions, means on said rotary member adapted to actuate said yarn guide mechanism and mechanism adapted to move said last-named means on said rotary member into and out of operative position.
63. A feed mechanism for a circular knitting machine having, in combination, a rotary member, a pair of movable yarn guides adapted to feed yarn to the needles of a knitting machine in a single feed, mechanism adapted to alternately move said yarn guides into operative position relatively to said needles, said mechanism being adapted to hold said yarn guides in said positions, means on said rotary member adapted to actuate said yarn guide actuating mechanism and mechanism adapted to move said last-named means into and out of operative position on said rotary member.
64. A circular machine for knitting striped goods having, in combination, a rotary member, a thread guide actuating mechanism including a rotary contact located on a stationary base, a contact member on said rotary member adapted to operate said first named contact member and means located on a stationary base constructed and arranged to move said contact member on said rotary member into and out of operative position.
65. A circular machine for knitting striped goods having, in combination, a rotary member, a contact member on said rotary member, a thread guide actuating mechanism constructed and arranged to hold a thread guide in operative position while a full course is being knitted on said machine and mechanism located on a stationary base constructed and arranged to move said contact member on said rotary member into and out of operative position relatively to said thread guide actuating mechanism.
66. A circular machine for knitting striped goods having, in combination, a rotary member, a contact member on said rotary member, a thread guide actuating mechanism including a contact member on a stationary base constructed and arranged to hold a thread guide in operative position while a full course is being knitted on said machine and mechanism located on a stationary base constructed and arranged to move said contact on said rotary member into and out of operative position relatively to the other of said contact members.
67. A circular machine for knitting striped goods having, in combination, a rotary member, a contact member on said rotary member, a pair of movable thread guides in one feed, a thread guide actuating mechanism including a contact member on a stationary base and constructed and arranged to alternately hold one of said thread guides in operative position while a full course is being knitted on said machine and mechanism located on a stationary base constructed and arranged to move said contact member on said rotary member into and out of operative position relatively to the other of said contact members.
68. A circular machine for knitting striped goods having, in combination, a rotary member, a contact member on said rotary member, a plurality of striping mechanisms on a stationary base, each including a movable thread guide and a contact member constructed and arranged to hold its respective thread guide in operative position during the knitting of a full course and mechanism on a stationary base constructed and arranged to move said contact on said rotary member into and out of position to operate the others of said contact members.
69. A circular machine for knitting striped goods having, in combination, a rotary member, a contact member on said rotary member, a plurality of striping mechanisms on a stationary base, each including a movable thread guide and a contact member constructed and arranged to hold its respective thread guide in opera-

tive position during the knitting of a full course and mechanism on a stationary base constructed and arranged to move said contact on said rotary member into and out of position to operate one or more of the others of said contact members.

In testimony whereof I have hereunto set

my hand in presence of two subscribing witnesses.

WILLIAM T. BARRATT.

Witnesses:

CHARLES S. KEHOE,
CHARLES S. GOODING.
